SEWING MACHINE

Richard Kaier, Cranford, N. J., assignor to The Singer Manufacturing Company, Elizabeth, N. J., a corporation of New Jersey

Application May 15, 1936, Serial No. 79,847

23 Claims. (Cl. 112—210)

This invention relates to sewing machines and more particularly to a high-speed lock-stitch sewing machine.

One of the objects of this invention is to provide an improved lock-stitch sewing machine which is capable of high-speed operation over a long period of time with the minimum of vibration.

Another object of this invention is to improve the lubrication of the feed-actuating mechanism and the provision of means for cooling the lubricating medium.

Another object of this invention is to provide an improved feeding mechanism capable of feeding the work either away from or towards the operator, characterized by its freedom from vibration, simplicity, reduction in weight of the reciprocating parts, and which is operable with the minimum of lost motion of the parts.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Figure 1 is a vertical sectional view taken through the center of a machine embodying my invention, some of the parts being shown in elevation.

Figure 2 is a bottom plan view showing the mechanism below the bed-plate.

Figure 3 is a vertical section taken substantially along the line 3—3 of Figure 2.

Figure 4 is a vertical section taken along the line 4—4 of Figure 1.

Figure 5 is a vertical section taken along the line 5—5 of Figure 2.

Figure 6 is a vertical section taken along the line 6—6 of Figure 2.

Figure 7 is a detail view of the linkage mechanism for imparting a feed-and-return movement to the feed-dog.

Figure 8 is a perspective view of the feed-actuating mechanism.

Figures 9 and 10 are diagrammatic illustrations of the movements of the feed-actuating mechanism for different set positions.

In the embodiment of the invention selected for illustration 10 represents the work-support or bed of the machine which carries the standard 11 and overhanging bracket-arm 12 terminating in a hollow-head 13. Journaled in the ball bear-

ings 14 and 15 carried by the bracket-arm is a needle-bar actuating shaft 16 having a driving pulley wheel 17 fixed to one of its ends. On the end of the needle-bar shaft, which terminates within the hollow-head 13, there is fixed the 5 crank 18 which, through the usual links drive the take-up 19, and the reciprocating needle-bar 20 carrying a needle 20' and journaled in the bearing 21 and 22 in the hollow-head.

Keyed to the shaft 16 is a sprocket-wheel 23 10 which is held against endwise movement on the shaft by the pulley wheel 17 and bearing 15. The bearing 15 abuts the shoulder 24 on the shaft 16 and a spring 25 is interposed between the bearing 24 and a shoulder on the bearing support 15 26. The purpose of this construction is to permit the shaft 16 to expand or contract without binding the parts and to maintain the hub of the crank 18 against the bearing 14 at all times.

At the ratio of 1 to 1, the sprocket-wheel 23 20 drives, through the clip-belt 27, a sprocket-wheel 28 fixed on the end of a shaft 29 which is located below the work-support 10. It will be noted that the sprocket-wheel and clip-belt are located on the outside of the standard and a guard 30 having a U-shaped cross-section is fixed to the standard to completely enclose the belt to prevent injury to the operator. This construction permits the guard 30 to be readily removed in order that a worn belt may be quickly and easily 30 replaced by a new one.

Adjacent the sprocket 28 the shaft 29 is journaled in a ball-bearing 31, the inner race of which is held in position between the shoulder 32 on the shaft and the hub of the sprocket 28. 35 The outer race member of the ball-bearing is held in position by a shoulder 33 on the bearing-lug 34 and a plate 35 fixed to the lug 34 by a screw 36.

The shaft 29 is also journaled in the bushings 37 and 38 carried by the lugs 39 and 40 which are made integral with the work-support 10. Secured to the shaft 29 intermediate the lugs 39 and 40 is a gear 41 which meshes with a gear 42 fixed to the hook-actuating shaft 43 which is 45 journaled in bearings carried by the lugs 39 and 40 and is prevented from endwise movement in its bearings by the gear 42 and a collar 44 secured to the shaft 43, both of which abut the bearing bushing 45 on opposite ends. The ratio 50 of the gears 41 and 42 is as 2 is to 1 and, therefore the hook-shaft 43 makes two complete rotations for each rotation of the shaft 29 and the needle-bar shaft 16.

Secured to the end of the shaft 43 is a rotary 55

hook 46 which cooperates with the needle 20' to form stitches. The loop-taker is the same as that shown and described in the Kessler Patent No. 1,995,278, dated Mar. 19, 1935.

5 The bed 10 has depending from its under side bearing lugs 47 and 48 in which is journaled a feed-lift rock-shaft 49. Fixed to the shaft 49 by the split hub 50 is an arm 51 which has its free end pivotally connected by the pivot-screw 52 to an end of the pitman 53, the other end of the pitman 53 embracing an eccentric 54 fixed to the shaft 29. It will be obvious from the foregoing that when the shaft 29 is rotated the shaft 49 will be rocked back-and-forth in its 15 bearings.

20 Journaled in the lugs 55 and 56 depending from the bed 10 is a rock-shaft 57 having fixed thereto by the split hub 58 an arm 59 to which is pivotally connected by the pin 60 a link 61 (see Figs. 5 and 8). Actuated by an eccentric 62 on the shaft 29 is a pitman 63 having its free 25 end bifurcated forming two arms 64 and pivotally secured between the arms, by the pivot-pin 66, is the other end of the link 61. Also pivotally secured on the pivot-pin 66 is the bifurcated end of a second or anchor link 67, the other end of which is pivotally secured to the free end of the arm 68 by the pivot-pin 69. The arm 68 is fixed, preferably, by a pin 70 to a feed- 30 adjusting shaft 71 which is journaled in the lugs 72 and 73 carried by the bed 10. Secured to the shaft 71 by the split hub 74 is an arm 75 carrying a pin 76 having a square head 77 (Fig. 1) apertured to receive a pin 78 held in the bell-crank 35 arm 79 by a set-screw 80. The bell-crank arm 79 is pivotally secured to the standard 11 by the shouldered screw 81 (Fig. 1) and threaded into the arm 79 is a clamping screw 82 which extends through a narrow slot in the standard 11.

40 Fixed to the rock-shaft 57 by the split hub 84 is an arm 85 (Fig. 6) to which is pivotally secured by the pivot-pin 86 one end of a feed-bar 87 carrying a feed-dog 88 which extends through suitable openings in the usual throat- 45 plate 89 and cooperates with the usual spring biased presser-foot 90. The other end of the feed-bar 87 is bifurcated to receive the usual stud 91 carried by the arm 92 which is fixed to the feed-lifting rock-shaft 49 by the split-hub 93.

50 From the foregoing it will be observed that when the shaft 29 is rotated the eccentric 62 will cause the pitman 63 to move back and forth. The links 61 and 67 are pivoted together to form a toggle-joint, and the pivot-pin 69 being held in 55 a set position by the arm 68, the pivotal connection 66 is constrained to move in the arc of a circle, indicated at A in Figure 10. The movement of the links from the full line position to the dotted line position (Figure 10) cause the link 61, through the arm 59, to move the rock-shaft 57 in a clockwise direction and thereby 60 impart a feeding movement to the feed-dog. When the pivotal point 69 is shifted to the position shown in Figure 9 the pivotal connection 65 66 is constrained to move in the arc of a circle indicated at B. It will be observed that when the links are moved from the position shown in full lines to the position shown in dotted lines (Figure 9) the link 61, though the arm 59, moves 70 the rock-shaft 57 in a counter-clockwise direction thereby imparting to the feed-dog a feeding movement which is the reverse of the feeding movement illustrated in Figure 10. It will be obvious from the above that the shaft 71 may 75 be turned so as to cause the feed-dog to feed the

work either forward or backward and the throw or feeding movement of the feed-dog may be regulated at will by simply adjusting the shaft 71 so as to bring the pivotal points 60, 66 and 69 nearer to or further out of alignment.

5 Depending from the bed 10 are the side walls 95 and 96 which connect the bearings for the shafts and the end walls 97 and 98 (Fig. 2). These side and end walls form a rectangular shaped enclosure. To the lower edge of the side 10 and end walls there is secured, preferably by screws, a plate 99 formed with depending heat dissipating fins 100 made of aluminum or other material having a high heat conductivity. The purpose of this construction is to completely 15 enclose the feed-actuating mechanism and the gears 41 and 42 so that they may be operated in a bath of oil, it being understood that the lower portion of the enclosure is filled with lubricant, preferably oil. The purpose of the heat radiating fins is to rapidly conduct the heat generated by the reciprocating parts from the oil.

20 It has been found that, when rotating or reciprocating parts are operated at high speed in an enclosure containing lubricant, a pressure develops and in order to relieve this pressure the rock-shaft 49 (Fig. 2) is provided with a longitudinal aperture 101 and a transverse aperture 102 which is connected with the aperture 101.

25 To lubricate the bearing bushings 37 and 38 30 for the shaft 29, these bushings extend beyond the lugs 39 and 40 (Fig. 1) into the enclosure and are formed with slots 103 and 104 which catch the oil which is splashed by the operation of the parts within the enclosure and this oil is fed to the bearing by the openings 105 and 106.

35 The bearings for the rock-shaft 57 are lubricated from the depressions 107 (Fig. 3) which collect the oil and feed it through the apertures 108 to the bearing surfaces.

40 From the foregoing description considered in connection with the accompanying drawings, the construction, manner of operation, and the several advantages of my improved sewing machine will be clearly and fully understood. While it 45 is preferred to employ the form, construction and arrangement of the parts herein shown and described in embodying the invention in a high-speed lock-stitch sewing machine, it will be understood that this construction and arrangement 50 is not essential to the broader aspect of the invention and the elements and their relative arrangements are susceptible of material variations.

Having thus set forth the nature of the invention, what I claim herein is:

55 1. Feeding mechanism for sewing machines having in combination a feed-rocker, an arm on said feed-rocker, a rotating shaft, an eccentric carried by said shaft, a pitman actuated by said eccentric, a link connecting said pitman to said arm and disposed at an angle to said pitman, and means for controlling the path of movement of the connection between said pitman and said link.

60 2. Feeding mechanism for sewing machines having in combination a feed-rocker, an arm on said feed-rocker, a rotating shaft, an eccentric carried by said shaft, a pitman actuated by said eccentric, a link connecting said pitman to said arm and disposed at an angle to said pitman, and a manually adjustable anchor link for controlling the path of movement of the connection between said pitman and said link.

65 3. Feeding mechanism for sewing machines 70

having in combination a feed-rocker, an arm on said feed-rocker, a rotating shaft, an eccentric carried by said shaft, a pitman actuated by said eccentric, a link connecting said pitman to said arm and disposed at an angle to said pitman, and a manually adjustable anchor link for controlling the path of movement of the connection between said pitman and said link, said links being pivoted together to form a toggle device.

4. Feeding mechanism for sewing machines having a work-support, comprising a feed-bar, a feed-dog carried thereby, means for imparting rising-and-falling movements to said feed-dog, a feed-rocker connected to said feed-bar, an arm on said feed-rocker, a rotating shaft journaled beneath the work-support, an eccentric carried by said shaft, a pitman actuated by said eccentric, a link connecting said pitman to said arm and disposed at an angle to said pitman, an anchor link for controlling the path of movement of the connection between said pitman and said first mentioned link, and manual means for controlling the position of said anchor link whereby the feed-dog may be caused to execute either a forward or a backward feeding movement.

5. Feeding mechanism for sewing machines having a work-support, comprising a feed-bar, a feed-dog carried thereby, a feed-rocker, an arm on said feed-rocker, a rotary shaft located below said work-support, an eccentric carried by said shaft, a pitman actuated by said eccentric, a link connecting said pitman to said arm and disposed at an angle to said pitman, an anchor link for controlling the path of movement of the connection between said pitman and said link, said links being pivoted together to form a toggle-joint, and manually adjustable means for controlling the position of said anchor link.

6. Feeding mechanism for sewing machines having a work-support comprising a feed-bar, a feed-dog carried thereby, a shaft journaled beneath said work-support, an eccentric actuated by said shaft, a feed-rocker, an arm on said feed-rocker, a pair of links pivoted together to form a toggle-joint one end of one of said links being pivoted to said arm and one end of the other of said links being constrained to move about a set pivot, means actuated by said eccentric for shifting the pivotal connection between said links to impart a forward feeding movement to the feed-dog, and means actuated by said shaft for imparting a rising-and-falling movement to said feed-dog.

7. A sewing machine having in combination, a work-support, a rotatable actuating shaft journaled beneath said work-support, a hook-shaft journaled beneath said work-support and arranged parallel to and above said actuating shaft, gearing connecting said shafts whereby the hook-shaft is caused to rotate at twice the speed of the actuating shaft, a pair of rock-shafts, said rock-shafts being disposed at opposite sides of said actuating shaft, a feed-bar carrying a feed-dog, means connecting one of said rock-shafts with said actuating shaft to cause the feed-bar to be raised and lowered, an eccentric carried by said actuating shaft, a pitman actuated by said eccentric, a link connecting said pitman to the other of said feed rock shafts, said link being disposed at an angle to said pitman, and a manually adjustable anchor link for controlling the path of movement of the connection between said pitman and said link.

8. A sewing machine having in combination, a bed, an actuating shaft journaled below said bed, a hook-shaft journaled below said bed and arranged parallel to said actuating shaft, a rotary hook operating about a horizontal axis and carried by said hook-shaft, means for actuating said hook-shaft at twice the speed of the actuating shaft, an eccentric carried by said actuating shaft, a pitman actuated by said eccentric, a link having one of its ends pivotally secured to operate about a set pivot and its other end pivotally secured to said pitman, a second link pivotally secured to said pitman, a feed-bar carrying a feed-dog, mechanism connecting the other end of said second link to the feed-bar for imparting a feeding movement to the feed-dog, and means for raising and lowering said feed-bar.

9. A sewing machine having in combination, a bed, an actuating shaft journaled below said bed, a hook-shaft journaled below said bed and arranged parallel to said actuating shaft, a rotary hook operating about a horizontal axis and carried by said hook-shaft, means for actuating said hook-shaft at twice the speed of the actuating shaft, an eccentric carried by said actuating shaft, a pitman actuated by said eccentric, a link having one of its ends pivotally secured to operate about a set pivot and its other end pivotally secured to said pitman, a second link pivotally secured to said pitman, a feed-bar carrying a feed-dog, mechanism connecting the other end of said second link to the feed-bar for imparting a feeding movement to the feed-dog, means for raising and lowering said feed-bar, and manually controlled means for varying the position of said set pivot.

10. A sewing machine having a work-support, an actuated shaft journaled beneath said work-support, a feed-bar, a feed-dog carried thereby, means actuated by said shaft for imparting a rising-and-falling movement to said feed-dog, an eccentric on said shaft, a feed-rocker pivotally supporting one end of said feed-bar, a member actuated by said eccentric, a link having one of its ends pivoted to said member and its other end constrained to move about a set pivotal pin, an arm on said feed-rocker, and a second link connecting said member to said arm.

11. A sewing machine having a work-support, an actuated shaft journaled beneath said work-support, a feed-bar, a feed-dog carried thereby, means actuated by said shaft for imparting a rising-and-falling movement to said feed-dog, an eccentric on said shaft, a feed-rocker pivotally supporting one end of said feed-bar, a member actuated by said eccentric, a link having one of its ends pivoted to said member and its other end constrained to move about a set pivotal pin, an arm on said feed-rocker, a second link connecting said member to said arm, and manual means for moving said pivotal pin to different set positions.

12. A sewing machine having in combination a work-support, a rotary shaft journaled beneath said work-support, a feed-bar carrying a feed-dog, means actuated by said shaft for imparting a rising-and-falling movement to said feed-dog, a feed-rocker connected to one end of said feed-bar, an arm carried by said feed-rocker, an eccentric carried by said shaft, a pitman actuated by said eccentric, a link having one of its ends pivotally connected to said pitman and its other end pivotally connected to the arm on said feed-rocker, an anchor link for controlling the

- path of movement of the pivotal connection between said first mentioned link and said pitman, manual means for controlling the position of said anchor link, said last named means comprising 5. a rock-shaft carrying an arm which is pivoted to said anchor link, and mechanism including a bell-crank lever for quickly shifting said rock-shaft about its longitudinal axis.
13. In combination with a sewing machine having a work-support, a lubricant containing chamber carried by and located beneath said work-support, a rotary shaft in said chamber, a feed rock shaft extending through one of the walls of said chamber, an eccentric on said rotary shaft and located in said lubricant chamber, and means also located within said chamber and connecting said rock-shaft to said eccentric for imparting an oscillatory movement to said rock-shaft.
14. In combination with a sewing machine having a work-support, a lubricant containing chamber carried by and located beneath said work-support, a rotary shaft extending into said lubricant chamber, a pair of feed rock shafts extending into said chamber, and means located within said chamber for oscillating said rock-shafts about their longitudinal axes.
15. A sewing machine having in combination a work-support, depending side and end walls carried beneath said work-support, feed-lift and feed-advance actuating mechanism located within the confines of said walls, a plate carried by said walls and enclosing said mechanism in an oil chamber, said plate being formed from metal having a high heat conductivity and being provided with depending heat radiating fins.
16. A sewing machine having in combination, a work-support, an actuating shaft journaled beneath said work-support, a hook-shaft journaled beneath said work-support and arranged parallel to said actuating shaft, gearing connecting said shaft to cause the hook-shaft to rotate at twice the speed of the actuating shaft, a feed-bar carrying a feed-dog, a pair of feed-rockers, means actuated by said actuating shaft for oscillating one of said feed-rockers to cause said feed-rocker to impart a rising-and-falling movement to said feed-dog, an eccentric on said actuating shaft, means actuated by said eccentric for oscillating the other of said feed-rockers to cause said feed-rocker to impart a feed-and-return movement to said feed-dog, and an oil chamber enclosing said gears and actuating means for the feed-rockers whereby said gears and actuating means are operated in a bath of oil.
17. A sewing machine having in combination, a work-support, side and end walls carried by said support and forming an enclosure, an actuating shaft extending through and journaled in said side walls, a hook-shaft and a pair of feed rock shafts extending through said side walls, mechanism located within the confines of said walls for actuating the hook-shaft at twice the speed of the actuating shaft and for oscillating said rock-shafts about their longitudinal axes, and a plate carried by said walls to form an oil chamber whereby said mechanism is operated in a bath of oil.
18. Feeding mechanism for sewing machines having in combination a feed-bar, a rotating shaft, an eccentric carried by said shaft, a pitman embracing said eccentric, a link connected at one end to said pitman and disposed at an angle to said pitman, means connecting the other end of said link to said feed-bar, and means for controlling the path of movement of the connection between said pitman and said link.
19. A sewing machine having a lubricant reservoir, a rotary shaft within said reservoir, mechanism actuated by said shaft and means for cooling the oil in said reservoir comprising a heat dissipating element formed from metal having a high heat conductivity and provided with heat dissipating fins.
20. In combination with a sewing machine having a work-support, walls defining a lubricant chamber and located beneath said work-support, a rotatable shaft within said chamber, a rock-shaft journaled in at least one of the walls of said chamber, a feed-bar operatively connected to said rock-shaft, an eccentric carried by said rotatable shaft, and operative mechanism located within said chamber and connecting said eccentric to said rock-shaft, whereby said mechanism and eccentric may operate in a bath of oil.
21. In combination with a sewing machine having a work-support, walls defining a lubricant chamber and located beneath said work-support, a rotatable shaft within said chamber, a rock-shaft journaled in at least one of the walls of said chamber, a feed-bar operatively connected to said rock-shaft, an eccentric carried by said rotatable shaft, operative mechanism located within said chamber and connecting said eccentric to said rock-shaft, and means extending through one of the walls of said chamber for imparting a rising and falling movement to said feed-bar.
22. In combination a sewing machine having a flat work-support, walls located beneath said work-support and defining a lubricant chamber, loop-taking and feeding mechanism below said work-support and outside of said chamber, loop-taker actuating and feed-actuating mechanism located within said chamber, and shafts extending through one of the walls of said chamber for actuating the loop-taker and feeding mechanisms.
23. A sewing machine having a flat work-support, walls located below said work-support and forming a lubricant chamber, a reciprocating needle located above said work-support, a loop-taker coordinated therewith and located beneath said work-support, feeding mechanism located beneath said work-support, said loop-taker and feeding mechanism being located outside of said chamber and in juxtaposed position to one of the walls of said chamber, and mechanism located within said chamber and journaled in said last mentioned wall for imparting a four-motion movement to said feeding mechanism and a loop-seizing movement to said loop-taker.

RICHARD KAIER.
